BIN OR HOPPER

Frederic Helmick, Fairmont, W. Va.

Application May 14, 1932, Serial No. 611,397

16 Claims. (Cl. 189—3)

This invention relates to improvements in bins or hoppers of a type particularly conceived for use in the handling and disposition of ashes or other materials of a hot or liquid nature.

5 The primary object of the invention is the provision of a bin or hopper constructed without the use of a structural steel frame and without any frame reinforcing structure.

Another object of the invention is the provision 10 of a bin or hopper composed of a plurality of sections secured together solely by attachment with one another to form a bin which in itself is of sufficient strength to serve the required purpose for which it is intended and which does not 15 need any frame for tying or binding the parts into their proper assembled positions.

A further object of the invention is the provision of an improved bin or hopper which in itself is sufficiently strong to be supported from 20 its under side and not need support from overhead.

Another and further object is the provision of an improved bin or hopper wherein a lining is supported in a novel and improved manner.

25 A still further object of the invention is the provision of an improved bin or hopper which is less subject to deterioration from vapors and acids that might seep through the lining or rise from below the bin than bins or hoppers now 30 known and in use.

Another and still further object of the invention is the provision of an improved bin or hopper which is watertight and the provision of an improved gate structure for controlling the discharge of materials from the bin.

35 Other specific objects, novel features of construction and improved results of the invention will be pointed out in more particular in the following description read in conjunction with 40 the accompanying drawings.

In the drawings:

Figure 1 is a view in side elevation of a double bin or hopper built in accordance with the present invention.

45 Fig. 2 is an end view of a bin or hopper.

Fig. 3 is a fragmentary detailed view in vertical section through one of the lower corners of the improved bin, a portion of the discharge gate being also shown in vertical section.

50 Fig. 4 is a view in side elevation illustrating the configuration of the cast sections making up the bin and illustrating the manner of attachment of the sections to one another.

Fig. 5 is a vertical sectional view through one 55 of the bin sections, the view being taken on the

line 5—5 of Figure 4 looking in the direction indicated by arrows.

Fig. 6 is a fragmentary view in side elevation of one of the upper corners of the bin and one method of supporting the bin.

Fig. 7 is a fragmentary view in end elevation of one of the lower corners of the bin and illustrating a modified manner of supporting the discharge gate.

Fig. 8 is a fragmentary bottom plan view illustrating the manner of attaching the wheels to the discharge gate.

Fig. 9 is a fragmentary view in vertical section taken on the line 9—9 of Figure 8 looking in the direction indicated by arrows.

Fig. 10 is a fragmentary view in vertical section, the view being taken on the line 10—10 of Figure 8.

Referring now to the drawings, which are illustrative of the inventive concept, and in which like parts are designated by similar reference numerals throughout the description, it will be seen by particular reference to Figure 1 of the drawings that a double bin or hopper is illustrated and that A designates one bin and B the adjacent bin. These bins have open tops and bottoms. The bin bottoms however are normally closed by gates C which are provided with wheels 11 supported on tracks 12 carried by hangers 13 which are bolted or otherwise suitably secured as at 14 to the bins.

Still referring to Figure 1 of the drawings, it will be seen that the bins are supported completely from their under side. At their ends adjacent their upper edges the bins carry outwardly projecting flanges 15 which rest upon brackets 16 carried by upright standards or posts 17. A cross beam 18 supports the bins intermediate their length as clearly indicated. The supports enumerated hold the bins against or closely adjacent the transverse floor supporting beam 19 of the building or structure within which the bins are positioned.

In the event the bin is positioned outdoors a supporting frame made up of upright beams 20 carrying cross beams 21 (see Fig. 6) which engage the flanges 15 of the bins can provide a suitable supporting medium.

Referring to the particular construction of the bins it will be seen by reference to Figures 4 and 5 of the drawings that they are made up of a plurality of sections 22. These sections are preferably composed of cast iron and are formed at their upper ends with a flange 23 and at their side edges with flanges 24. These flanges tend

to strengthen the sections and furthermore the side flanges 24 are provided with a plurality of openings 25 through which bolts or rivets 26 pass for securing the sections firmly together.

- 5 Intermediate their length the sections are formed with outwardly extending U-shaped pockets 26. All of these pockets have closed ends as indicated at 27 and are disposed in horizontal separated parallel relation and extend throughout the width of the bin sections so that when the bin sections are bolted together there are formed continuous rows of pockets throughout the length and breadth of the bin.

At their lower ends the cast bin sections 22 are provided with outwardly extending pockets 28 and these pockets also have closed ends as indicated at 29. The pockets 26 do not extend at all beyond the inner face of the section body but the pockets 28 at the lower ends of the sections have their lower walls 30 extending inwardly beyond the inner face of the section body and the end closure 29 also extends inwardly as clearly indicated in Figure 5 of the drawings.

From the foregoing it will be seen that by properly shaping the sections a bin of any desired configuration can be built up from a plurality of cast sections and that these sections can be readily and quickly secured together by bolts or rivets to build up a complete bin. The resulting structure as a consequence has no supporting frame nor is any frame required to tie together the sections to form the bin. The bolts or rivets securing the bin sections together can be tightened down sufficiently to prevent any leakage of water or other material from the bin.

The bins or hoppers for handling ashes or material of a hot or liquid nature are preferably lined either with refractory brick or some other suitable material of a similar nature.

40 By reference to Figure 3 the manner of lining my improved bin is illustrated wherein it will be seen that within the pockets 26 and 27 are positioned the header course of bricks 31 and 32 of the lining. The bricks making up these header courses are supported within these pockets and extend outwardly beyond them to support the remaining rows or tiers of brick which are indicated at 33. Thus it will be seen that although the bin has an open bottom a refractory lining is supported within the bin in a novel and improved manner and that the method of support comprises outwardly struck header course brick supporting pockets. This improved manner of supporting the lining is a drastic departure from the usual method now known and in use wherein the lining is supported by means of members which extend inwardly into the bin beyond the inner faces of its walls.

60 The wheeled gates C are of course for controlling the discharge of material from the bins. In ordinary practice the bins are sufficiently elevated to permit a railway car or other vehicle to be placed beneath the bin to receive the discharge of contents therefrom. These gates are made up of cast iron sections and are in the form of a box having in their bottoms a refractory brick or other suitable lining 35 surrounded by side walls 36 and an end wall 37 which extend considerably above the upper face of the lining. The front or 65 end wall 38 of the gates is much lower than the other walls of the box making up the gate with the result that any fluid contents of the bin can drain outwardly over the low front wall 38 of the discharge gate. These box gates are larger in 70 size than the bottom openings in the bins and the

upwardly extending side and end walls 36 and 37 overlap the lower ends of the bins whereby all moisture will drain into the gate and be discharged over the low end wall 38 thereof.

5 The wheels 11 which support the gate are carried by plates 39 which are bolted as at 40 into the depressed seats 41 provided in the under face of the gate bottom 42. In the preferable form the rollers 11 have a chilled iron tread and roller bearings.

10 If it is desired the track for the discharge gate need not necessarily be carried by the brackets heretofore described but can be supported upon a suitable cross beam 43 which has its ends supported in the vertical uprights 17.

15 As a means of operating the gate and moving it along its track I have illustrated in Figure 2 of the drawings a power piston 44 having connection through a suitable rod 45 and its associated parts with a projection 46 on the bottom of the gate C. 20 As I claim no protection for the gate operating mechanism no particular detailed description is given of this part of the structure and it will be readily apparent that other suitable mechanical means could be substituted as desired for operating the gate and moving it along its track.

25 In describing the lining for the bin, bricks have been suggested as a lining medium. It should be understood however that the lining material could be cast iron or any other suitable lining material 30 having projections extending into the pockets of the bin sections for supporting the lining in place.

35 Attention is also called to the fact that the bin in itself is particularly strong and rigid. This is due largely to the fact that each bin section really constitutes a series of boxes the edges of which are formed by the section flanges and the outwardly extending lining supporting pockets.

40 What I claim is:

1. An improved bin or hopper, comprising a plurality of cast sections formed with flanged portions extending outwardly at right angles to the section body, said flanges adapted to be secured together to provide a complete structure, and said sections intermediate their length intended to provide outwardly extending pockets for supporting a lining.

45 2. An improved bin or hopper, composed entirely of a plurality of cast sections, said sections being strengthened by flanges extending outwardly at right angles from their edges and by indented horizontally disposed pockets positioned intermediate the length of the sections, said flanges providing a means for securing the sections together, and said pockets providing a means for supporting a lining.

50 3. An improved bin or hopper, comprising a plurality of cast sections secured together solely by attachment with one another, said sections being strengthened by flanges which extend outwardly at right angles from their edges and by indented pockets horizontally disposed intermediate the length of the sections, and said sections in themselves providing a bin of sufficient strength to support itself and load when supported above the ground at its underside only.

55 4. An improved bin or hopper, having an open top and an open bottom, comprising a plurality of cast sections secured together solely by attachment with one another, said sections at their 60 abutting edges provided with flanges extending outwardly at right angles to the sections, said flanges adapted to be bolted together, pockets indented in said sections for supporting a lining, supports carried by said sections adjacent the 65

lower end of the bin, and a gate below the open bin bottom and movable on said supports.

5. An improved section for a bin or hopper composed of a plurality of sections, comprising a cast section member formed at its edges with flanges extending outwardly at right angles to the member and provided intermediate the length of its body portion with horizontally disposed indented pockets.

10. 6. An improved bin or hopper, comprising a plurality of flanged cast sections secured together solely by attachment to one another, said sections intermediate their length being indented to form pockets extending outwardly in respect to the bin, said sections being further indented adjacent their lower edges to form pockets which extend outwardly in respect to the bin, said last-mentioned pockets having their lower walls extending inwardly into the bin beyond the inner face of the bin wall, for the purpose described.

7. In a bin or hopper, U-shaped horizontally disposed pockets indented in the side walls of the structure intermediate the length of said walls and extending outwardly in respect to the interior of the bin, and a lining for said bin supported by engagement with said pockets.

8. An improved bin or hopper, comprising a plurality of sections each indented intermediate its length to form a horizontally disposed pocket extending outwardly in respect to the bin interior, a lining for said bin and said lining having projections extending into said pockets for supporting the lining on the inner walls of said sections.

9. An improved bin or hopper, composed of a plurality of cast sections secured together to form of themselves a complete structure, each of said sections comprising a body portion having at its upper end a flange disposed at right angles to its body portion and extending outwardly therefrom in respect to the bin interior, similarly disposed flanges at the vertical edges of said section, a plurality of horizontally disposed pockets indented into the body portion of the sections and extending throughout their widths and having their open sides at the interior of the bin, one of said pockets being positioned at the lower end of the section, the flanges at the vertical edges of the section extending over and closing the ends of the pockets at the edges of the sections, and means to secure the vertical flanges of the several sections together to provide the completed structure.

55. 10. An improved bin or hopper, composed of a plurality of sections secured together, each of said sections comprising a body portion having at its upper end a flange extending outwardly therefrom in respect to the bin interior, similarly disposed flanges at the vertical edges of said sections, a plurality of horizontally disposed pockets indented into the body portion of the sections and extending throughout their widths and hav-

ing their open sides at the interior of the bin, the flanges at the vertical edges of the sections extending over and closing the ends of the pockets, and means to secure the vertical flanges of the several sections together.

5. 11. In an improved bin or hopper, walls defining said hopper, a lining for said hopper, horizontally disposed pockets in the lower ends of said hopper walls, and said pockets having a bottom extending inwardly into the hopper beyond the plane of the walls for supporting said hopper lining.

10. 12. In an improved bin or hopper, walls defining said hopper, certain of said walls inclined at an angle to the vertical, a plurality of horizontally disposed pockets indented into said walls and having bottoms and tops extending outwardly from said walls at right angles thereto, horizontally disposed pockets positioned at the lower ends of said walls and having bottoms and tops 20 extending outwardly therefrom at an acute angle, and the bottoms of the last mentioned pockets also extending inwardly into the bin beyond the plane of the bin walls.

15. 13. In an improved bin or hopper having a lining composed of bricks, walls defining said hopper, a plurality of horizontally disposed pockets positioned intermediate the depth of said walls and in horizontal spaced relation therein, said pockets adapted to receive one end of a brick while the 30 other end of the brick extends into the hopper beyond the hopper wall to form a support for the bricks positioned on said lining above said open ends of said pockets, the parts operating as and for the purpose described.

35. 14. A bin of the kind described composed of a plurality of rectangular box-like sections having the sides secured together to form horizontal and vertical reinforcing ribs for the complete bin, each section being provided with lateral pockets, members arranged in said pockets and a sectional lining supported in the bin by said members.

15. A bin formed of a plurality of rectangular box-like sections with the sides in contact with one another, means passing through said sides 45 for securing said sections together to form a complete bin with vertical and horizontally disposed reinforced ribs, each section being provided with rectangular pockets to receive lining members, said lining members forming supports for other 50 lining members.

16. A bin of the kind described comprising a plurality of rectangular box-like sections having the sides secured together to form vertical and horizontal reinforcing ribs for the complete bin, 55 each section being provided with lateral projecting pockets, said pockets forming horizontally disposed reinforcing ribs, lining members arranged in said pockets projecting therefrom and other lining members supported by the protruding portion of said members.

FREDERIC HELMICK.
